COCKTAIL SHAKER

John W. Ebstein, Roslyn Heights, N.Y., assignor, by
mesne assignments, to Federal Enameling & Stamping
Co., Pittsburgh, Pa., a corporation of Michigan

Filed Feb. 10, 1960, Ser. No. 59,341

Term of patent 14 years

(Cl. D2—3)

Figure 1 is a side elevation of a cocktail shaker showing my new design, with the cover shown in separated position;

Figure 2 is a rear elevation of the cocktail shaker;

Figure 3 is a front elevation thereof;

Figures 4 and 5 are top plan views of the cover element illustrated in closed position and in pouring position, respectively; and

Figure 6 is a cross-section on the line 6—6 of Figure 4.

The side of the cocktail shaker opposite that shown in Figure 1 is a mirror image of the side shown.

I claim:

The ornamental design for a cocktail shaker, as shown and described.
